VARIABLE PITCH PROPELLER

Isaac Leonard Ellwood, 2d, and Blake Burton,
Williams Bay, Wis.

Application January 4, 1936, Serial No. 57,618

2 Claims. (Cl. 170—68)

The invention relates to a variable pitch propeller and more especially to an automatic pitch controlled propeller.

- The primary object of the invention is the provision of a propeller of this character, wherein in through centrifugal force the angular disposition of the blades of the propeller are automatically changed so that when the propeller is in use the velocity of the wind when least on 10 the blades of the propeller the centrifugal force will be nil and as the wind increases a centrifugal action is set up due to increased rotation of the propeller so that the blades will become automatically adjusted so as to assure a variation 15 in the degrees of pitch of such blades dependent on the amount of centrifugal force exerted thereon so as to have the propeller obtain a near or constant revolution thereby minimizing variation and wear.
- Another object of the invention is the provision of a propeller of this character, wherein the blades thereof are supported in a novel manner so that under varying wind velocity the said blades through centrifugal force will be 25 caused to automatically change their pitch and thus assuring near constant propeller revolution, the propeller being of novel construction and is adaptable for driving and driven purposes.
- A further object of the invention is the provision of a propeller of this character, which is comparatively simple in construction, thoroughly reliable and efficient in its operation, possessing but few parts with resultant strength and durability and also one which is comparatively inexpensive to manufacture.

With these and other objects in view, the invention consists in the features of construction, combination and arrangement of parts as 40 will be hereinafter more fully described, illustrated in the accompanying drawings, which disclose the preferred embodiment of the invention, and pointed out in the claims hereunto appended.

45 In the accompanying drawings:

Figure 1 is a plan view of a propeller constructed in accordance with the invention.

Figure 2 is a sectional view through one of its blades.

50 Figure 3 is a view similar to Figure 2 showing the blade positioned at a different angle and automatically changed by centrifugal force.

Figure 4 is a perspective view of the pitch changing shaft and hub for one of the blades 55 of the propeller.

Figure 5 is a sectional view on the line 5—5 of Figure 2.

Figure 6 is a sectional view on the line 6—6 of Figure 1.

Similar reference characters indicate corresponding parts throughout the several views in the drawings. 5

Referring to the drawings in detail, A designates generally a portion of a power shaft either for driving or driven purposes and carrying the 10 propeller constituting the present invention and hereinafter fully described. Fitted upon this shaft A is a blade carrying ring 10, it having a tapered center opening 11 for accommodating the tapered end 12 of the shaft A, the said ring 15 being keyed or splined upon said shaft. Rotatably fitted with the shaft 12 next to the ring 10 is a synchronizing disk 13 having formed therein tangentially disposed slots 14 which are preferably equally distanced or spaced from each 20 other and have slidably fitted therein coupling yokes 15 for the swivel connection of the annularly grooved inner end 16 of pitch changing shafts 17 which are radially arranged with relation to the ring 10 and have fixed thereto hubs 25 18 which are rotatably and slidably fitted in hollow tubular stems 19, each at its inner end being fixed in a capped bearing 20 on the ring 10. Upon this stem 19 turns a blade 21, there being three in number in this instance for the 30 completed propeller. The blade 21 for a larger portion of its length is centrally longitudinally slit at 22 for occupancy of the stem in said slit while the outer wider tip end 23 of the blade which carries a weight 24 in the nature of a 35 blade support is made fast by a coupling 25 with the outer end of the shaft 17 which is passed centrally through the stem 19. The blade 21 has the slit 22 widened at 26 next to the tip 23 and at 27 next to the inner end of said blade and 40 this widened portion 27 of the slit opens through the inner end of the said blade while bridging the said widened portion 27 of the slit at opposite sides of the blade 21 are clips 28 to loosely embrace the stem 19 between annular abutments 45 29, formed on the said stem and spaced the required distance from each other, the stem 19 at its outer end being outturned to provide an annular abutment 30 within the widened portion 26 of the slit 22 next to the tip 23 of said blade. 50 Thus the blade 21 with its tip is slidably and rotatably journaled on the stem 19 and the sliding displacement of the said blade on the stem is limited by the annular abutments 29 and 30, respectively. 55

The stem 19 at its inner end is fixed in its companion capped bearing 20 by a screw 31 having a reduced inner end 32 loosely engaged in a spiral channel or groove 33 formed in the hub 18 on the control shaft 17 and this hub slides radially to produce the turning of the same with the resultant adjustment of the blades to vary the pitch of the same.

In the working of the propeller under wind velocity as the same increases or decreases against the blades 21 of the propeller through centrifugal force or centrifugal action the pitch or angular disposition of the blade will be automatically changed and this coming about by the turning of the hubs 18 on the shafts 17 which are moved by the slotted disk 13, these shafts being swiveled in the yokes 15 working in the slots 14 in said disk 13.

The disk 13 has connected to it a series of coiled tensioning springs 34, these being also connected to the ring 10 and function to return the blades to a neutral position as that shown in Figures 1 and 2 of the drawings, whence the yokes 15 will have traveled in the slots 14 to the inner ends of these slots, the disk 13 being rotated in a direction by the tension of the springs 34 for this purpose.

It should be apparent from Figures 1, 2 and 3 of the drawings that when the velocity of the wind increases and strikes the blades 21 this causes a momentary increase in propulsion of the propeller. Because of this increase centrifugal force causes the weighted tips 23 of the blade to move outwardly, thereby pulling upon the shafts 17 which rotates the disk 13 against the resistance of springs 34. This outward movement of the shafts 17 through the hubs 18 thereon engaging the pin ends 32 of the screws 31, that is to say, these pin ends 32 working in the grooves or channels 33 in said hubs 18 automatically effect a changing of the pitch of the blades 21 so that the propeller through pitch variation of its blades will have a near constant revolution during the variations in the velocity of the wind current.

The ring 10 has built upon its face next to the disk 13 an annular track 35 for the play of the said disk thereon during the changing of the position of the disk under the automatic pitch changing action of the propeller.

The stems 19 for the blades 21, each has fitted in its outer end a bushing 36 through which passes the shaft 17 so as to center the shaft within the stem 19 particularly at the outer end thereof while the hub 18 centers said shaft 17 at the inner end of the stem. In the changing of the pitch of the blades 21 these have a limited reciprocating movement on the stems 19 and such movements are restricted by the abutments 28 and 30 as will be apparent from Figures 1 and 2 of drawings.

The weights 24 on the tips 23 of the blades are preferably of segmental form and are made secure by suitable fasteners 37 which pass through the weights and said tips while the yokes 15 are loosely held in the slots 14 in the disk

13 as at 38 to prevent the pulling out of these yokes to free the same from the disk, the clips 23 being secured to the blade 21 by fasteners 38. The caps of the bearings 20 are separably fastened in place by fasteners 40 and these capped bearings hold the shafts 17 with the stems 19 and the blades 21 radially disposed with respect to the ring 10, which is a carrier body for the blades.

The clockwise and counter-clockwise movements of the disk 13 result in the pitch changing of the blades as the shafts 17 are displaced and through the hubs 18 thereon the said shafts rotate or turn the blades 21 to the pitch necessary under ordinary action in the rotation of the propeller.

It is, of course, understood that changes, variations and modifications may be made in the invention as come properly within the scope of the appended claims without departing from the 20 spirit of the said invention or sacrificing any of its advantages.

What is claimed is:

1. In a propeller of the character described a rotary shaft, a blade carrying ring carried by said shaft, a synchronizing disk rotatable with respect to said ring and having tangentially disposed slots, coupling yokes swiveled in said slots, pitch changing shafts radially supported with relation to said ring, tubular stems about said pitch changing shafts, propeller blades rotatable about and shiftable on said stems and having the pitch changing shafts fixed thereto, hubs fixed to said pitch changing shafts and having spiral connections with the stems, spring tensioned means connected with the ring and disk for normally holding the coupling yokes at the inner ends of the tangential slots in said disk, the blades having wider portions at their outer ends and provided with longitudinal slots accommodating said stems, and weights on the wider ends of said blades.

2. In a propeller of the character described a rotary shaft, a blade carrying ring carried by said shaft, a synchronizing disk rotatable with respect to said ring and having tangentially disposed slots, coupling yokes swiveled in said slots, pitch changing shafts radially supported with relation to said ring, tubular stems about said pitch changing shafts, propeller blades rotatable about and shiftable on said stems and having the pitch changing shafts fixed thereto, hubs fixed to said pitch changing shafts and having spiral connections with the stems, spring tensioned means connected with the ring and disk for normally holding the coupling yokes at the inner ends of the tangential slots in said disk, the blades having wider portions at their outer ends and provided with longitudinal slots accommodating said stems, weights on the wider ends of said blades, and bearings on the ring and accommodating the hubs of said pitch changing shafts.

ISAAC LEONARD ELLWOOD, II.
BLAKE BURTON.
